UNITED STATES PATENT OFFICE.

WALTER J. SCOTT, OF WOONSOCKET, RHODE ISLAND.

STOP MOTION FOR DRAWING FRAMES.

Application filed May 31, 1928. Serial No. 281,970.

This invention relates to an improved stop motion for drawing frames; and has for its object to provide in such a stop member an electric circuit controlled by a movable contact member located above the upper bearing block for the spindle, and against which member the sliver is deposited when an end breaks down or when the sliver is fed faster than it is taken up, the building up of which will effect a movement of the circuit closure to stop the machine.

5

A further object of the invention is to provide a sliver receiving chamber adjacent the upper end of the spindle on one or more of the 15 walls of which chamber is located a movable circuit closing member whereby when a surplus of the sliver collects in this chamber its weight or pressure effects a movement of one or more of these circuit closers to stop the 20 machine.

With these and other objects in view, the invention consists of certain novel features of construction, as will be more fully described, and particularly pointed out in the 25 appended claims.

In the accompanying drawings:

Figure 1 is a side elevation showing my improved circuit closing device as applied to a drawing frame.

30 Figure 2 is an enlarged view partly in section showing the front wall plate as supported on the hinged door of the bearing block, the circuit closing member being mounted on this plate.

35 Figure 3 is a plan view of the parts shown in Figure 2.

Figure 4 is a top view of the bearing block showing a second cooperating circuit closing member as mounted on the upper face of the 40 block.

Figure 5 is an elevation sectioned on line 5—5 of Figure 4 showing the two contact members, one on the front wall and one on the upper face of the bearing block.

45 Figure 6 is an enlarged elevation partly in section showing portions of the draft rolls and their position relative to the upper spindle bearing block, also illustrating the building up of the sliver in the chamber which 50 building up affects the circuit closers on the walls of the chamber to stop the machine.

Figure 7 is a view partly in section showing the tripper and solenoid which effects the releasing action of the tripper to permit the throwing of the belt to stop the machine.

55 Figure 8 is a general diagrammatic view

illustrating the electric circuit as connected to the circuit closures and to the stop motion of the machine.

It is found in practice that in some instances the upper end of the spindle is substantially flush with the upper face of the upper bearing block and that when for any reason the sliver is broken or is fed faster than it is taken up on the package or spool, it has a tendency to be folded back and forth upon itself and so build up on the upper face of this bearing block and finally fall over to become tangled up with the other running parts. My present invention locates the circuit closing members in such a way that the building up of this sliver upon this bearing block will stop the machine, and I have herein shown one means for accomplishing this which is to support a front wall plate on this block opposite the spindle bearing to extend up a substantial distance above the face of the block, which wall serves to cooperate with the upper face of the block and the draft rolls to provide a chamber into which this surplus sliver may be folded and on this wall plate I mount a contact finger normally spaced at its free end from its contact to maintain an open circuit, whereby when sliver for any reason is not taken up as fast as fed by the draft rolls and builds up in this chamber, it is caused to lie against this delicately poised contact finger and move its free end to close the circuit and stop the machine. In other cases I locate one or more contact 90 fingers on the upper face of the bearing block itself so that the weight of the sliver in being built up upon the block moves these circuit closing members to close the circuit and stop the machine. This sliver when so folded into the chamber, after the machine is stopped, may be readily unfolded and its end passed again through the spindle and attached to the spool and the operation continued without wasting the sliver which was 100 nicely folded into the chamber; and the following is a detailed description of the present embodiment of this invention and showing one means by which these advantageous results may be accomplished:

With reference to the drawings, 10 and 11 designate the upper and lower draft rolls respectively and 12 the bearing block for the upper end of the spindle 13. These blocks are supported on an arm 15 from the rail 14 in the desired position to receive the upper end of the spindle. The front edge of each

of these blocks is provided with a plate 16 hinged at 17 to swing open and permit the positioning of the upper end bearing of the spindle and on this gate I have formed an upwardly-extending wall plate 18 on the inner face of which is supported a flexible contact finger 19 which is insulated from the plate as at 20 where it is permanently secured at its lower end by a bolt 21. This bearing block is positioned relative to the rolls 10 and 11 to cooperate therewith and form the bottom wall of the chamber while the lower roll 11 will serve as a rear wall for the chamber, and the plate 18 will serve as a front wall for the chamber into which the sliver is deposited.

In some instances instead of relying alone upon the contact finger 19 on the front wall plate 18 I mount either one or a pair of fingers 22 upon the upper face of the bearing block which fingers are also connected to an electric circuit 33 whereby the mere weight of the built-up sliver will force these fingers 22 down to engage their contacts and close the circuit and stop the machine.

I have herein shown a package spool 23 as mounted on the spindle 13 which spool rests upon a rail 24 which is raised and lowered through the usual rack 25 and pinion 26 and the sliver 27 after passing through the upper end of the spindle and out through an opening 28 therein is fed through an eye 29 down along the flyer arm 30 and through its guide eye 31 and is led to be wound upon the spool 23, whereby if for any reason the sliver becomes broken at any point between the nip of the draft rolls 10 and 11 and the point where it is laid upon the spool or package 23, it is no longer drawn through the spindle but will be deposited in the chamber 32 formed by the walls above described and folded back and forth upon itself as best illustrated in Figure 6, whereby the weight of the built-up folds will act upon the circuit closing members 22 or the pressure of these folds will move the contact finger 19 to close the circuit and stop the machine.

After the machine is stopped this nicely folded sliver which is not injured may be again threaded through the spindle and around onto the spool or package and the machine again started without wasting that folded portion which otherwise would fall down over the bearing block to become entangled with the other running parts of the machine and be destroyed, besides taking considerable time to remove the waste portions from engagement with the parts around which it has become wound or twisted.

One means of stopping the machine when the circuit is closed is best illustrated in Figures 7 and 8, in which the contact fingers are caused to close the circuit through the wires 33 and the closing of this circuit serves to energize the solenoid magnet 34 to withdraw

the latch 35 and release the lever 36 which under action of spring 37 moves the belt shift 38 to carry the belt from the tight pulley 39 to the loose pulley 40 and so stop the machine.

By my improved motion the machine is stopped when the sliver is not feeding properly and the free end portion is preserved and is not injured and the end may be again threaded up without wasting the folded portion.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:—

1. In a stop motion for drawing frames, a set of draft rolls, a spindle, an upper bearing block for said spindle, a package for taking up the sliver as fed by said rolls, a chamber formed adjacent said bearing and rolls, an electric circuit, and an electric circuit closure in said chamber positioned to be affected by the accumulation of the sliver in said chamber to close the circuit and stop the machine.

2. In a stop motion for drawing frames, a set of draft rolls, a spindle, an upper bearing block for the spindle, means including the rolls and the block for forming a sliver receiving chamber, an electric circuit, a flexible circuit closing member in the chamber arranged to be moved by a collected mass of sliver in the chamber to close the circuit and stop the machine.

3. In a stop motion for drawing frames, upper and lower draft rolls, a spindle, means operated by the spindle for laying the sliver onto a bobbin as fed by the rolls, an upper bearing block for said spindle, means cooperating with said block and rolls to form a sliver receiving chamber, an electric circuit closer in the chamber positioned to be affected by pressure of collected sliver in the chamber for closing the circuit to stop the machine.

4. In a stop motion for drawing frames, a set of draft rolls, a spindle, means for winding the sliver into package form as fed by said rolls, walls forming a sliver receiving chamber adjacent the upper end of the spindle, an electric circuit, a flexible member supported on said chamber walls and affected by the collecting of sliver in said chamber to close the circuit and stop the machine.

5. In a stop motion for drawing frames, a set of draft rolls, a spindle, means for winding the sliver into package form as fed by said rolls, an upper bearing block for said spindle, walls including said block, and rolls forming a sliver receiving chamber above the block, an electric circuit, a flexible member supported on said chamber walls and affected by the collecting of sliver in said chamber to close the circuit and stop the machine.

6. In a stop motion for drawing frames, a set of draft rolls, a spindle, means for winding the sliver into package form as fed by said rolls, an upper bearing block for said spindle, a vertically disposed plate supported on said block, said plate co-operating with said block and rolls to form a sliver receiving chamber, an electric circuit, a flexible member supported on said front wall plate arranged to be moved by a deposit of sliver in said chamber to close the circuit and stop the machine.

In testimony whereof I affix my signature.

WALTER J. SCOTT.
